[57] CLAIM

The ornamental design in an I.D. brake drum gauge for heavy duty vehicle brakes, as shown and described.

DESCRIPTION

FIG. 1 is a front elevational view of an I.D. brake drum gauge for heavy duty vehicle brakes showing my design in an extended position;

FIG. 2 is a right end elevational view thereof;

FIG. 3 is a left end elevational view thereof;

FIG. 4 is a front elevational view thereof in the fully retracted position;

FIG. 5 is a top plan view of FIG. 4.
